UNITED STATES PATENT OFFICE

92,870

DESIGN FOR A REVERSIBLE WALL SHELF

Mary L. Stone, Arlington, Mass.

Application November 22, 1933, Serial No. 49,820

Term of patent 3½ years

To all whom it may concern:

Be it known that I, MARY L. STONE, a citizen of the United States of America, residing at Arlington, in the county of Middlesex and State of Massachusetts, have invented a new, original, and ornamental Design for a Reversible Wall Shelf, of which the following is a specification, reference being had to the accompanying drawing, forming part thereof

In the drawing:

Fig. 1 is a perspective view of a reversible wall

shelf showing my new design, the shelf being shown in one of its positions;

Fig. 2 is a view similar to Fig. 1 showing the wall shelf in inverted position.

The shelf is adapted to be fastened to a wall in the position of Fig. 1 or in that of Fig. 2.

I claim:

The ornamental design for a reversible wall shelf, as shown and described.

In testimony whereof I affix my signature.

MARY L. STONE.
